UNITED STATES PATENT OFFICE.

ADOLPH W. OLSON, OF McINTOSH, MINNESOTA.

VÉHICULE.

1,108,216.

Specification of Letters Patent. Patented Aug. 25, 1914.

Application filed February 4, 1914. Serial No. 816,548.

To all whom it may concern:

Be it known that I, ADOLPH W. OLSON, a citizen of the United States, residing at Mc-Intosh, in the county of Polk and State of Minnesota, have invented certain new and useful Improvements in Vehicles, of which the following is a specification, reference being had to the accompanying drawings.

This invention relates to certain improvements in vehicles and has relation more particularly to a device of this general character especially designed and adapted for travel over snow or ice; and the object of the invention is to provide a device of this general character having means of a novel and improved construction whereby the same may be driven by motor and whereby the direction of travel of the vehicle may be controlled with convenience and facility.

The invention consists in the details of construction and in the combination and arrangement of the several parts of my improved vehicle whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be the better understood, I will now proceed to describe the same with reference to the accompanying drawings, wherein—

Figure 1 is a view in top plan, with certain of the parts in section, of a vehicle constructed in accordance with an embodiment of my invention; Fig. 2 is a view in side elevation of the device as illustrated in Fig. 1, with certain of the parts omitted; Fig. 3 is an enlarged transverse sectional view taken through the forward part of the device, as shown in Fig. 1; Fig. 4 is an enlarged transverse sectional view of the body of the vehicle, as herein disclosed, such section being taken at a point at which certain of the sprocket wheels herein included are adapted to be positioned; Fig. 5 is an enlarged fragmentary view in top plan, with a part in section, of a fragment of a drive chain, herein included; Fig. 6 is a fragmentary view in elevation and partly in section, showing the manner in which the drive chain operates, a portion of such chain and a coacting sprocket wheel being shown in dotted lines; Fig. 7 is a view in front elevation of a run-

ner included in the present embodiment of my invention; Fig. 8 is a view in side elevation of the runner illustrated in Fig. 7; Fig. 9 is a sectional view taken on the line 9—9 of Fig. 1; Fig. 10 is a sectional view taken on the line 10—10 of Fig. 1; and Fig. 11 is a view in front elevation of a calk employed in the present embodiment of my invention.

As disclosed in the accompanying drawings, 1 denotes the body of my improved vehicle of predetermined dimensions and preferably formed of a hard wood, although I do not wish to be understood as limiting myself as to material. At predetermined points upon the body 1 is suitably supported, through the medium of the bearings 2, the transverse shafts 3—3, on each of which are suitably affixed the spaced sprocket wheels 4—4, the diameter of each of such wheels being such as to have the same projected through an opening 5 produced in the plate 6, suitably secured to and resting upon the intermediate plate 7 which is rested upon and secured to the body 1, the opening 5 being in register with a slot 8 produced in such plate 7 and disposed longitudinally thereof and terminating at its extremities with the openings 9, disposed through the body 1, as is clearly shown in the accompanying drawings, such openings 9 being connected by the slot 10 disposed through such body 1, for a purpose which will be hereinafter more fully set forth, and it is to be observed that the slot 10 is offset relative to the opening 5 and that the slot 8 is of greater width than the slot 10. The slot 8 is adapted to afford in connection with the body 1 and the plate 6 a suitable channel through which is adapted to pass the lower stretch of an endless sprocket chain 11, which is also directed around corresponding sprocket wheels 4—4 on the respective shafts 3. The chain 11, as herein disclosed, has a side bar of two of its links provided with a depending arm 12 adapted to extend through the slot 10 of the body 1 and terminate therebelow, the projected portion of such finger being provided with the transverse plate or calk 14 adapted to impinge the snow or ice over which the device is adapted to travel whereby it will be observed that a ready and convenient means is afforded for creating the requisite propulsion of the vehicle. In order to reduce to a minimum the resultant wear of the chain and the calk upon the ad-

adjacent surfaces of the body 1, I employ, as herein disclosed, the longitudinally disposed wear-plates 15 and 16, the plates 15 being disposed at the inner marginal portion of the slots 10 at the upper face of the body 1, while a plate 16 is disposed at each side of the slots 10 at the lower or under face of the body 1.

Interposed between the shafts 3-3 and bridging substantially the entire space therebetween is a platform 17 maintained in proper spaced relation relative to the body 1 through the medium of the supporting trusses or brackets 18, the opposite marginal portions of such platform being provided with the longitudinally directed grooves 20 substantially L-shaped in form with the feet 21 thereof inwardly directed, the upper stretches of the chains 11 being adapted to travel through such feet 21, while the stem portions of the slot permit an unobstructed travel of the arms 12. Coacting with and suitably secured to the platform 17 is the cover member 22 of such dimensions as to entirely inclose the platform and of such a height as to in no wise interfere with the travel of the calks 14.

From the foregoing description, it is thought to be obvious that the chains 11 are substantially entirely inclosed at all times which, in a device of this character, is of material advantage, as is believed to be obvious to those skilled in the art to which my present invention appertains.

While any means, which will operate with facility, may be employed for imparting the requisite travel to the chains 11, I prefer to employ the construction shown in the accompanying drawings, wherein one of the transverse axles 3 and preferably the rear of such axles has affixed thereto intermediate the sprockets 4, the worm gear 23 adapted to mesh with a worm 24 affixed to the driving shaft 25 of the motor 26, herein disclosed as mounted upon the body 1 adjacent the rear end thereof. A detailed description of the motor 26 need not be given, it is thought, at this time, although it might be well to state that it is preferred that it be of an internal combustion type and be provided with a suitable clutch 27 and speed control 25', each of which being operatively connected, with suitable levers 29 positioned in convenient proximity to the seat 30, herein disclosed as mounted upon the cover member 22.

The body 1 or skee, as it is known, has its forward end portion upturned, as at 31, and rearwardly of such upturned portion and in close proximity thereto the body 1 is provided with the upstanding bracket or truss 32 reinforced by the brace 33 and to which truss is suitably secured the transversely disposed bow-shaped member 34 produced preferably of spring steel and having its free extremities directed rearwardly relative to

the body 1 and terminating a predetermined distance beyond the opposite sides of such body. The free end portions of the bow-shaped member 34 are operatively connected, as at 35, with the short runners 36, which runners are further united through the medium of the transverse bar 37 having its central portion in pivotal engagement, as at 38, with the body 1. As illustrated in the accompanying drawings, this pivotal engagement between the bar 37 and the body 1 is afforded through the medium of the depending ball member suitably affixed to the under surface of the bar 37 and which is adapted to be accommodated within the socket 39 produced in the upper extremity of the post 46 suitably anchored to the upper surface of the body 1, or more particularly to the upper plate 6. The cover member 22 is provided adjacent its lower end and at 85 opposite sides thereof with the outwardly disposed guide plates or extensions 41, in each of which is slidably supported a block 42, such block being so constructed as to readily receive the foot of the occupant of the vehicle and whereby such block may be reciprocated by the operator, as is believed to be self-evident. The forward end of the block 42 is operatively connected with the bar 37 through the medium of a link 43 whereby it will be readily perceived that the direction of travel of the vehicle may be controlled with convenience and facility.

It is to be observed that the extremities of the spring member 34 curve or incline upwardly and thereby create a steady pressure on the runners 36 and thus maintain the body 1 normally against jar incident to lateral movement. It will also be noted that the spring member 34 assists in the steering operation. When it is desired to turn in a certain direction, for example to the right, the movement of the bar 37 under the influence of the member 34 will cause the left side of the body 1 to rise, whereby turn of the body 1 is greatly facilitated.

I have found in practice that it is of advantage to provide each of the runners 36 with a shoe 44 having the heel portion thereof provided with a longitudinally directed knife 45 positioned at substantially the transverse center of the shoe.

In order to effectively protect the sprockets 4 from snow so that their operation will not be interfered with, I find it of advantage to inclose the space between the body 1 and the platform 7 with the side boards 17^a, as is clearly shown in the accompanying drawings, such side boards being disposed in substantially close proximity to the engine 26 in order that a convenient guard may be afforded. It is also to be observed that it is my purpose to have the arms 12 capable of detachable engagement as I have found in practice that when the device 130

is intended to travel over snow such arms should be longer than when the vehicle is intended to travel over ice.

From the foregoing description, it is thought to be obvious that a vehicle constructed in accordance with my invention is of an extremely simple and comparatively inexpensive nature and is particularly well adapted for use by reason of the convenience and facility with which it may be operated and whereby the direction of its travel may be controlled and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

Having thus fully described my invention what I desire to claim and secure by Letters Patent, is:

1. A device of the character described including a body having longitudinally disposed elongated slots extended therethrough intermediate its length, such slots being angular in cross section, transversely disposed shafts supported by the body adjacent the opposite ends of the slots, a platform supported by the body and positioned between the shafts and substantially bridging the space therebetween, such platform being provided with spaced parallel grooves in its upper surface angular in cross section, endless members operatively connected with the shafts and traveling through the slots of the body and the grooves of the platform, arms carried by the endless members adapted to project through the slots of the body, calks carried by the projected portions of the arms, means for rotating one of the shafts.

2. A device of the character described including a body having longitudinally disposed elongated slots extended therethrough intermediate its length, such slots being angular in cross section, transversely disposed shafts supported by the body adjacent the opposite ends of the slots, a platform supported by the body and positioned between the shafts and substantially bridging the space therebetween, such platform being provided with spaced parallel grooves in its upper surface angular in cross section, endless members operatively connected with the shafts and traveling through the slots of the body and the grooves of the platform, arms carried by the endless members adapted to project through the slots of the body, calks carried by the projected portions of the arms, means for rotating one of the shafts, and a cover member carried by the platform substantially entirely inclosing the same.

3. A device of the character described comprising an elongated body, a resilient member projecting beyond opposite sides of the body, and runners positioned at opposite sides of the body and connected with the free end portions of such member.

4. A device of the character described comprising an elongated body, a resilient member projecting beyond opposite sides of the body, a bar in pivotal connection with the body and projecting beyond opposite sides thereof, runners positioned at opposite sides of the body and connected to the bar, and operative connections between the runners and the extremities of the member.

In testimony whereof I hereunto affix my signature in the presence of two witnesses.

ADOLPH W. OLSON.
